CLIP FOR TUBES AND THE LIKE

Max Famely, 141 South Ave., Garwood, N.J.

Filed July 3, 1961, Ser. No. 65,791

Term of patent 14 years

(Cl. D54—1)

FIG. 1

FIG. 2

FIG. 3

FIGURE 1 is a front elevational view of the clip for tubes and the like embodying my new design, with a fragmentary tube shown in broken lines for illustrative purposes only;

FIGURE 2 is a view taken from the bottom of FIG. 1; and

FIGURE 3 is a view taken from the right side of FIG. 2.

I claim:

The ornamental design of a clip for tubes and the like, as shown and described.
